The ornamental design for an electric wok, as shown and described.

DESCRIPTION

FIG. 1 illustrates an isometric perspective view 100 of an electric wok according to an exemplary embodiment of the present invention.

FIG. 2 illustrates a top plan view 200 of an electric wok according to an exemplary embodiment of the present invention.

FIG. 3 illustrates a bottom plan view 300 of an electric wok according to an exemplary embodiment of the present invention.

FIG. 4 illustrates a right side elevational view 400 of an electric wok according to an exemplary embodiment of the present invention.

FIG. 5 illustrates a left side elevational view 500 of an electric wok according to an exemplary embodiment of the present invention.

FIG. 6 illustrates a front elevational view 600 of an electric wok according man exemplary embodiment of the present invention; and,

FIG. 7 illustrates a back elevational view 700 of an electric wok according to an exemplary embodiment of the present invention.

The broken lines shown in the drawings are for illustrative purposes only and form no part of the claimed design.
